CLAIM

I claim the ornamental design for a suspension assembly for a vehicle, as shown and described.

DESCRIPTION

FIG. 1 is a perspective view of a suspension assembly for a vehicle.

FIG. 2 is a front elevation view of the suspension assembly for a vehicle of FIG. 1, the rear elevation view being a minor image thereof.

FIG. 3 is a perspective view of an extension member of the suspension assembly for a vehicle of FIG. 2, shown apart from the entire suspension assembly for a vehicle.

FIG. 4 is a front elevation view of the extension member of FIG. 3, the rear elevation view being a mirror image thereof.

FIG. 5 is a top plan view of the extension member of FIG. 3.

FIG. 6 is a bottom plan view of the extension member of FIG. 3; and,

FIG. 7 is a cross-sectional view of the extension member taken along line 7-7 of FIG. 5.

The broken lines in the drawings represent features of the suspension assembly for a vehicle that form no part of the claimed design.
